WILLARD C. BRINTON, OF NEW YORK, N. Y., ASSIGNOR TO TERMINAL ENGINEERING COMPANY, INC., OF NEW YORK, N. Y., A CORPORATION OF NEW YORK

JACK

Original application filed January 9, 1923, Serial No. 611,568. Divided and this application filed November 21, 1928. Serial No. 321,283.

This invention relates to jack construction and this application is a division of application Serial No. 611,568, filed January 9, 1923.

The invention relates more particularly to 5 a jack structure developed for use in elevating and lowering truck platforms on trucks, but it should be understood that the structure is capable of general application and of use in any device where jacks are employed.

10 The invention has for its salient object to provide a jack structure that is simple and practical in construction, can be readily assembled, and is so designed that the maximum lift or stroke can be obtained for a 15 minimum over-all dimension or length.

Further objects of the invention will appear from the following specification taken in connection with the drawings, which form a part of this application, and in which

20 Fig. 1 is a top plan view of a jack structure constructed in accordance with the invention, and

25 Fig. 2 is a sectional elevation, partly broken away, of the structure shown in Fig. 1.

The jack structure briefly described comprises a housing, a thimble rotatably mounted in the housing, and a jack screw disposed in the thimble and operative connections 30 whereby as the thimble is rotated the jack screw will be elevated or lowered. The end thrust is taken by a thrust bearing disposed between the upper end of the thimble and the lower end of the housing and of relatively 35 large diameter whereby the thimble will be supported without adding to the length of the over-all dimension of the jack structure. The thimble is mounted around a bushing and a bearing is disposed between the bushing and spindle in alignment with a sprocket wheel by which the thimble is rotated. Thus the thrust of the chain on the sprocket wheel is taken up by the bearing. In addition to these features, the thimble and jack structure 40 are so mounted in the housing as to facilitate the assembling of the parts and also the disassembling or removal of the structure carried thereby from the housing.

Further details of the invention will appear from the following description.

The detailed construction of the jack shown in Figs. 1 and 2 will now be described. The various parts of the jack are supported in a housing 70 which is designed to be mounted in corners of the vehicle frame 10 to which it is secured by cap screws 71 or in any other suitable manner. Supported by the housing 70 and projecting downwardly out of the latter, is a thimble 72 of the form shown which at its upper end is provided with a sprocket or pulley 73 adapted to receive the driving chain or rope 22. Interposed between the lower part of the housing 70 and the top part of the thimble 72 is a thrust bearing 75, preferably of the ball type. 55 The location of the thrust bearing 75 within the housing 70 instead of at the lower end of the thimble effects a material saving in the over-all length of the jack. 60

Arranged within and supported by the 70 thimble 72 is a jack screw 76, which at its lower end is provided with a squared end 78 adapted to enter a square hole through the bottom of the thimble 72. The bottom end of the thimble 72, adjacent both ends of the 75 squared hole through the latter, is machined to flat surfaces so that flange 79 on the screw 76 may seat properly on the bottom of the thimble 72, and so that a washer 84 secured by a cap screw 82 to the squared end 78 of the 80 jack screw may seat properly against the bottom of the thimble 72. As shown in Fig. 2, the cap screw 82 is prevented from accidental loosening by means of a wire threaded through a hole therein and holes in the outer 85 end of the thimble 72. With this construction it will be obvious that the jack screw 76 is rigidly secured to and rotatable with the thimble 72.

Arranged for movement within the thimble 72 is an elevating quill 86 having secured within its lower end a nut 87 which cooperates with the jack screw 76. The nut 87 may be conveniently made of Babbitt metal, in a well known manner. The elevating quill 86 is provided with key-ways 88 and with a flange 90 at its bottom end, for purposes hereinafter described. At its upper end the quill 86 is closed by a screw plug 91 of the form shown, which may have in its top a slot 92 100

adapted to receive a screw driver. Rotatably mounted in a recess in the top of the jack screw 76 is a ball 93 which engages the inside of the plug 91 when the quill 86 is in its lowermost position, thereby limiting the downward movement of the latter. Secured in the top of the housing 70 is a bushing 95 which serves as a guide for the elevating quill 86. The form of this bushing will be apparent from Figs. 1 and 2, from which it will be evident that the bushing is provided with four radially extending lugs 97 adapted to fit in recesses in the housing 70. The bushing 95 and the housing 70 are thus connected by what may be called a bayonet joint, and after being adjusted to any desired position, the bushing 95 may be held from rotation by metal strips 100 adapted to fit in slots in the top of the bushing 95 and in slots between the lugs 98, said strips being secured to the top of the bushing 95 by screws 101.

As will be obvious from Fig. 2, the bushing 95 is provided with a downwardly extending portion which not only serves as a guide for the quill 86 but also serves as a guide bearing for the thimble 72, rollers 104 being preferably interposed between the thimble 72 and the bushing 95 in order to reduce the friction between those parts to a minimum. Attention is called to the fact that the rollers 104 are disposed in line with or in the plane of the sprocket wheel 73 and thus take the chain thrust. The bushing 95 also serves to support keys 105 which may be secured therein in any suitable manner and enter the key-ways 88 in the quill 86, thereby preventing the latter from rotating.

The mode of operation of the jack just described will be obvious. Rotation of the thimble 72, through the medium of the jack or cable 22 which is in engagement with the sprocket or wheel 73, causes rotation of the jack screw 76. As the jack screw 76 is rotated, the nut 87 and the quill 86, to which said nut is attached, move axially, being prevented from rotary movement by the engagement of the key-ways 88 with the keys 105. The quill 86 is limited in its upward movement by the engagement of the flange 90 with the bottom of the bushing 95; and the downward movement of the quill 86 is limited by the engagement of the plug 91 with the ball 93 in the upper end of the screw 76. The downward thrust of the quill 86, due to the load which it is lifting, is transmitted through the nut 87 to the screw 76 and from the latter to the thimble 72 which is supported on the thrust bearing 75 in the housing 70. The tendency for the thimble 72 to move laterally is offset by the guide bearings comprising the rollers 104 interposed between the thimble 72 and the bushing 95.

When a plurality of jacks of the type above described are to be driven in synchronism by a single chain or cable, the upper ends of

all of the jacks may be adjusted to the same level by regulating the angular positions of the bushings 95 of the various jacks, this being permitted by the bayonet construction heretofore described.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. In a hoisting jack, a housing by which the jack may be supported, a rotary thimble supported by said housing and projecting downwardly out of the latter, a thrust bearing arranged between the lower part of said housing and the top part of said thimble, a jack screw arranged within said thimble and secured to the latter at its bottom end, an elevating quill having a nut cooperating with said jack screw and arranged for axial movement within said thimble, a bushing removably connected to said housing and arranged to serve as a guide for said quill, means cooperating with said quill and said bushing for restricting the quill to axial movement, a guide bearing between said thimble and said bushing, and means for rotating said thimble whereby the jack screw is rotated and the elevating quill is caused to move axially.

2. In a hoisting jack, a housing by which the jack may be supported, a rotary thimble supported by said housing and projecting downwardly out of the latter, a thrust bearing arranged between the lower part of said housing and the top part of said thimble, a jack screw arranged within said thimble and secured to the latter at its bottom end, an elevating quill having a nut cooperating with said jack screw and arranged for axial movement within said thimble, a bushing connected to said housing and arranged to serve as a guide for said quill, a bayonet connection between said bushing and said housing adapted to permit the bushing to be removably connected to said housing in a plurality of angular positions, means cooperating with said quill and said bushing for restricting the quill to axial movement, a guide bearing between said thimble and said bushing, and means for rotating said thimble whereby the jack screw is rotated and the elevating quill is caused to move axially.

3. In a hoisting jack, a housing by which the jack may be supported, a rotary thimble supported by said housing and projecting downwardly out of the latter, said thimble having at its top a driving wheel integral therewith, a thrust bearing arranged between the lower part of said housing and a top of said thimble below said driving wheel, a jack

screw arranged within said thimble and secured to the latter at its bottom end, an elevating quill having a nut cooperating with said jack screw and arranged for axial movement within said thimble, a bushing connected to said housing and arranged to serve as a guide for said quill, means cooperating with said quill and said bushing for restricting the quill to axial movement, and a guide bearing between the top of said thimble and said bushing.
